(57) **CLAIM**

The ornamental design for an element of a container for personal use, as shown and described.

DESCRIPTION

FIG. 1 is a perspective view of an element of a container for personal use, showing our new design.

FIG. 2 is a left elevational view thereof.

FIG. 3 is a right elevational view thereof.

FIG. 4 is a front elevational view thereof.

FIG. 5 is a back elevational view thereof; and,

FIG. 6 is a top elevational view thereof.

The broken line showing of a container depicts environmental subject matter only and forms no part of the claimed design.
